UNITED STATES PATENT OFFICE.

ROBERT LAMONT, OF BROOKLYN, NEW YORK.

HAT-BLOCKING MACHINE.

SPECIFICATION forming part of Letters Patent No. 236,233, dated January 4, 1881.

Application filed November 29, 1880. (No model.)

To all whom it may concern:

Be it known that I, ROBERT LAMONT, of Brooklyn, in the county of Kings and State of New York, have invented an Improvement in 5 Hat-Blocking Machines, of which the following is a specification.

Hat stretchers and dies have been made for stretching, forming, and shaping hats, and in some instances the blocks have been operated 10 by a treadle. Pins have also been permanently introduced into the dies used for shaping hats, which pins have held the fabric while being operated upon.

My improvement is made with reference to 15 applying heat to the hat while being stretched and shaped, so as to allow the same to assume the proper form more easily than it would if the stretching and shaping operations were performed upon the hat in a wet condition, 20 and the hat is also dried upon the blocks; and I provide a peculiar device for moving one of the hat-blocks and stretching the hat, and there are removable pins for holding the edge 25 of the hat-brim in position upon the block.

In the drawings, Figure 1 is an elevation of 30 the steam-table and vertical section of the hat-blocks. Fig. 2 is a plan of the same; and Fig. 3 is a section, in large size, of the pin-holders.

The steam-table A is made as a hollow metal 35 box, to which steam is conveyed by a suitable pipe, b, and cock, and the water of condensation is discharged by the pipe c. This table is supported by a frame or legs. Upon one side of the table A there is fixed a standard, d, and at the other side a pulley, e.

The hat-block is made of metal, in two parts, 40 e and f. These blocks are of the proper shape for the crown and brim of the hat, and the same will be varied according to the style of hat to be stretched and shaped. The block e is secured by a bolt, i, passing through the slotted upper end of the standard d, and the block f has connected to it a wire cord or strap, l, passing over the pulley e' to the spring m and treadle n.

The bases of the blocks e and f are made 45 with slots in line with each other, and into which the contractile spring o is introduced, the ends of said spring being hooked upon the screw-hooks inserted into the hat-blocks.

This contractile spring draws the blocks e f together when not otherwise operated upon.

There is a stop, r, upon the top of the steam-table, that is provided with a slot and clamping-screw, so as to be adjustable, and the same 55 determines the amount of movement that can be given to the block f by the treadle, and, consequently, the size to which the hat is stretched. There are holes in the brim portions of these hat-blocks e f, near their edges, 60 into which are inserted the short cylinders s, preferably of brass, that can be easily taken out or replaced. Their upper ends, however, are level with the surface of the brim of the block, and through each there is a central hole 65 for the reception of an ordinary pin, the head being downwardly and the point projecting enough for the hat-brim to be secured by being pressed down upon the points of the pins after the hat has been placed upon the blocks. 70

It is to be understood that the heat from the steam-table is communicated to the blocks, and these being a heavy mass of iron the heat is retained and accumulates, and that when a moist hat or hat-body is placed upon the hat- 75 blocks it rapidly becomes heated, and the operator spreads the brim and secures it upon the pins. He then partially separates the hat-block sections by pressure upon the treadle, and the treadle may be held by one of the 80 teeth of its rack-bar v, with which it is brought into contact. After the hat becomes warmer and partly stretched, the treadle may, if desired, be further depressed until the blocks are separated to the proper limit, or the full limit 85 to be stretched may be done at one operation, and the hat is then allowed to dry or set while under strain, so as to properly shape the hat.

It will be evident that the spring between the cord or strap and the treadle allows for 90 the treadle being moved without a sudden strain being applied to the hat; hence the fabric is gradually stretched and injury avoided.

In case of either pin becoming injured another pin can be introduced after the short cylinder has been lifted. 95

The pins that hold the edges of the brim are preferably small, so as not to injure the fabric; hence they are liable to be injured. In my mode of introducing these pins they can be 100

very easily replaced, and ordinary brass or iron pins can be used, and they hold the brim out while being stretched.

I claim as my invention—

- 5 1. The combination, with the steam-heating table, of the hat-blocks *e* and *f*, the standard connecting the block *e* to the table, the cord or strap *l*, the treadle *n*, and the adjustable stop *r*, to limit the opening movement of the blocks, substantially as set forth.
- 10 2. The combination, with the hat-blocks *e* and *f*, of the removable cylinder *s*, introduced into holes in the rim of the hat-blocks, and having central holes for pins, substantially as set forth.
- 15 3. The hat-blocks made in two parts and adapted to being heated, in combination with

a treadle and a spring, and connection from the treadle to the hat-block, whereby the spring acts to stretch the hat, and sudden or harsh movement of the blocks is prevented, substantially as set forth.

4. The hat-block made in two parts, in combination with a contractile spring within the base, a steam-table or similar means for heating the block, and mechanism for drawing the blocks apart, substantially as described.

Signed by me this 26th day of November, A. D. 1880.

ROBERT LAMONT.
